UNITED STATES PATENT OFFICE

FREDERICK CLIFFORD TODD, OF CINCINNATI, OHIO, ASSIGNOR TO THE STUEBING & AUTOMATIC MACHINE CO., OF CINCINNATI, OHIO, A CORPORATION OF OHIO

METAL BINDING FOR CALENDARS

Application filed November 28, 1930. Serial No. 498,607.

This invention relates to the art of binding calendars, hangers, banners and the like with a metal binding and to such bindings and method of making the same.

It is the practice in binding such articles to use a previously formed V-shaped strip of sheet metal which is applied to one edge of the article and then attached thereto by a hand brake or other suitable device for the purpose. In order to enable the bound article to be suspended, the binder inserts a metal tab in the form of an eyelet in the binding strip prior to the operation of the hand brake and this operation serves to attach the tab.

In thus incorporating a loose tab, it frequently happens that the tab assumes an angular position or otherwise becomes misplaced with the result that the mounting is defective, or the operator may forget to insert a tab and thus there is no means of suspending the calendar after the binding is completed. In any case, considerable time is expended during the binding operation in picking up the tabs and manually placing them within the strip.

In accordance with my invention, the tab is permanently secured to the strip preferably when the strip is manufactured, and the binder merely has to place the strip with attached tab on the margin of the calendar or other article and bend the same in the usual manner in the hand brake. Not only does this method insure the presence and proper placing of the tab but it very materially saves time and labor in the binding operation.

The combined strip and tab has a further advantage in that it may be more conveniently handled by the binder. Binding strips are generally produced in automatic machines which cause them to become nested or they are so nested by the manufacturer for convenience and safety in packing and shipment. Heretofore, considerable time has been expended by the binder in separating these strips as they tend to hold together rather tightly. When the individual strips are provided with tabs in accordance with the present invention, these tabs may be

readily grasped and the strips quickly and easily separated in their order of nesting.

These and other objects, general and particular, will be best understood by reference to the accompanying drawing, in which:

Fig. 1 is a detail perspective view of one of the formed elements preparatory to assembly;

Fig. 2 is a detail perspective view of another of the elements;

Fig. 3 is a perspective view of a complete binding strip;

Figs. 4 to 7 inclusive illustrate the binding operation, and

Fig. 8 shows the relative position of the strips when nested for shipment.

Referring to the drawing, a strip of sheet metal is bent into substantially V-form or trough as shown in Fig. 1, generally with a narrow fold as 1 and a wide fold as 2, the widths of the folds depending on the size of the calendar or other article to be mounted. A metallic tab as 3, shown in detail in Fig. 2, is inserted into the bend of the strip substantially in the position shown in Fig. 3 and attached to a side of the strip by piercing the metal strip and tab preferably simultaneously and upsetting the burr thus formed as at 4 or by welding, riveting, cementing or otherwise. Where only one tab is to be used, this generally would be placed at the longitudinal center of the strip. It will be evident that the attaching of the tab to the strip may take place before or after the bending of the strip, as preferred. The strip thus formed is ready to be used in the binding operation.

Referring to Fig. 8, it will be seen that when the strips are nested, the tabs 3 extend one beyond the other with the tab of the first strip outermost, so that these strips may be removed successively by the binder by grasping such outermost tab. Furthermore, the tabs prevent the strips from nesting tightly and thus separation is facilitated.

The binding operation is illustrated in Figs. 4 to 7. The strip with attached tab is placed by the binder in the hand brake or other device for the purpose in the usual

manner, and one edge 5 of a calendar 6 or other article to be bound is inserted into the bend of the strip in substantially the manner indicated in Figs. 4 and 7. The operation 5 of the hand brake at this time serves to again fold the strip and with it the marginal portion of the calendar as illustrated in Figs. 5 and 6. The pressure then exerted tightly secures the strip upon the calendar. 10 It will be evident from the foregoing description that the method forming in part the subject matter of the present invention saves time and labor and insures proper binding. The strips with attached tabs may 15 be manufactured economically and they very materially facilitate the binding operation. 20 As many possible embodiments may be made of the features of the above invention and as the art herein described may be varied considerably, all without departing from the scope of the invention, it is to be understood that all matter herein set forth or shown in the accompanying drawing is 25 to be interpreted as illustrative and not in a limiting sense.

I claim:

1. As an article of manufacture, a metallic binding for calendars and the like comprising a strip of sheet metal substantially V-shaped in cross-section, and a metal tab, and means for securing said tab to a face of said strip before the article to be bound is inserted.
2. As an article of manufacture, a metallic binding for calendars and the like comprising a strip of sheet metal bent into substantially V-shape with the bend extending longitudinally of the strip, and a tab separate and distinct from said strip, and means for securing said tab to an inner face of the strip and projecting beyond the margin thereof.
3. As articles of manufacture, a plurality of metallic binders for calendars and the like each comprising a strip of sheet metal adapted to be bent to form a binder, a tab attached to said strip, and said metallic bindings being nestable in one another whereby packing and shipping of said bindings is facilitated.
4. An article of manufacture, for use in connection with a bound article of the class wherein a metallic strip is formed to have a V-shape cross section, and an edge of the article to be bound is inserted in the trough of said V together with a tab for hanging the bound article, and the metal strip is then folded to bind the article and tab together, comprising a metal strip having a V cross section, a tab, and means for fastening said tab to a face of said strip.

5. In an edge supporting structure for a stack of sheets, a trough-shaped strip adapted to grip the edge of said sheets, a tab hav-

ing a portion thereof adapted to be gripped between said strip and said stack of sheets, and means for securing said tab to said strip.

6. An article of manufacture for binding edge portions of a stack of sheets making up a calendar or the like comprising a binder including a thin strip of steel bent along a longitudinal line to form a trough having two walls one of the walls being wider than the other, and a metal tab having one end thereof positioned in the trough of said strip and attached to the wider of said walls by upsetting burrs formed by simultaneously punching the wall and tab; the trough of said strip of steel being capable of receiving an edge portion of the stack of the sheets whereby the edge portion and the tab may be bound together by folding the wider of said walls along a second longitudinal line to clinch the narrower of said walls, a portion of the tab and the edge portion of said stack of sheets therebetween.

7. A binder for binding together edge portions of a stack of sheets comprising a thin strip of steel having a V-shaped cross-section, one of the sides of the V being higher than the other; and a tab having one end thereof positioned in the V of the V-shaped cross-section and attached to one of the sides by upsetting burrs formed by simultaneously punching at least one hole through said side and tab; said strip being capable of receiving an edge portion of said stack of sheets in the V of its V-shaped cross-section whereby the tab, edge portions of sheets and binding strip may be clinched together.

8. In an edge supporting structure for a stack of sheets, a trough shaped strip adapted to grip edge portions of said sheets, and a tab comprising a part positioned to be gripped together with said edge portions by said strip, said tab being secured to a side of said strip.

In testimony whereof, I have signed my name to this specification this 24th day of November, 1930.

FREDERICK CLIFFORD TODD.
